(57) **CLAIM**

The ornamental design for a bonnet lamp, as shown and described.

DESCRIPTION

FIG. 1 is a front, right-side perspective view of a bonnet lamp showing our new design;

FIG. 2 is a front view thereof;

FIG. 3 is a back view thereof;

FIG. 4 is a right-side view thereof. A left-side view of the bonnet lamp is a mirror image of the right-side view, and therefore omitted;

FIG. 5 is a top view thereof; and,

FIG. 6 is a bottom view thereof.
